UNITED STATES PATENT OFFICE.

HENRY A. WEIHMAN, OF PHILADELPHIA, PENNSYLVANIA.

DESIGN FOR A HANDLE FOR SPOONS.

SPECIFICATION forming part of Design No. 22,252, dated March 7, 1893.

Application filed January 4, 1893. Serial No. 457,285. Term of patent 14 years.

To all whom it may concern:

Be it known that I, HENRY A. WEIHMAN, of the city and county of Philadelphia and State of Pennsylvania, have invented a new and original Design for Handles for Spoons, &c., of which the following is a specification.

My new design is illustrated in the accompanying drawings, in which:

Figure 1 is a plan view of the front of a spoon to the handle of which my design is applied; and Fig. 2 is a similar view of the back of the spoon.

The design consists of the highly ornamental scroll pattern shown arranged about the handle adjacent to the edge leaving the intermediate or inner portion unornamented. The scroll pattern on the face or front of the handle is of considerable breadth and extends to a considerable distance from the edge so as to leave a comparatively small unornamented portion. The particular character of the pattern is clearly shown in the drawings. It con-

sists of foliated scrolls of highly ornate character with the conventional crown pattern A at the end or extremity. On the back of the handle, the scroll pattern is much narrower so as to leave a comparatively wide unornamented intermediate portion and is also less ornate.

The design is applied only to the handle and may without change or modification and without affecting the character of the design be applied to forks and other objects.

In Fig. 1 of the drawings I have indicated in dotted lines a fork applied to the handle.

What I claim is—

A design for a handle of spoons &c, substantially as herein shown and described.

In testimony of which invention I have hereunto set my hand.

HENRY A. WEIHMAN.
